UNITED STATES PATENT OFFICE.

WILLIAM KELSO, OF PITTSBURGH, PENNSYLVANIA, ASSIGNOR TO McCONWAY & TORLEY COMPANY, OF PITTSBURGH, PENNSYLVANIA, A CORPORATION OF PENNSYLVANIA.

CAR-COUPING.

1,148,020.

Specification of Letters Patent. Patented July 27, 1915.

Application filed November 19, 1913. Serial No. 801,857.

To all whom it may concern:

Be it known that I, WILLIAM KELSO, a citizen of the United States, residing at Pittsburgh, in the county of Allegheny and 5 State of Pennsylvania, have invented certain new and useful Improvements in Car-Couplers; and I do hereby declare the following to be a full, clear, and exact description of the invention, such as will enable 10 others skilled in the art to which it appertains to make and use the same.

My invention relates to the construction of car couplers, and especially to those couplers of the vertical plane type wherein are 15 combined a pivoted knuckle, a knuckle opening device and a vertically movable locking pin or lock for the knuckle.

The invention is particularly directed to the attainment of the unlocking and knuckle-opening actions by a limited vertical movement of the means for actuating the locking member, the coupler being thereby rendered especially suitable for use where the vertical space between the underside of the 25 car platform and the top of the coupler head is comparatively small, as is generally the case in passenger car construction.

To this end, the main feature of my invention embraces the combination with a 30 coupler head having a slot for the entrance of a lever which actuates the lock, of a lever which is pivoted on and projects into the coupler head, a knuckle pivoted on the head, and a vertically movable lock actuated by 35 the lever which projects into the coupler head.

The pivoted actuating lever which projects into the coupler head and actuates the lock is preferably connected with the locking member by a curved link member which 40 is pivotally connected with the actuating lever and with the lock member to thus permit the link connection to accommodate itself to the various positions of the actuating lever, and such a construction embodies a further feature of my invention.

There are other and further features of invention, residing in particular features of construction and special combinations, all 50 as will hereinafter more fully appear.

In the drawings chosen for the purpose of illustrating my invention, the scope whereof is pointed out in the claims, Figure 1 is a view of a coupler embodying my invention,

the view being partly in plan and partly in 55 horizontal section on the line 1—1, Fig. 2; Fig. 2 is a vertical transverse section of the coupler shown in Fig. 1, the view being taken on the line 2—2, Fig. 1, and the parts being in their locked positions; Fig. 3 is a 60 sectional view similar to Fig. 2, the parts being in the positions they assume when the knuckle is rotated to open position by means of the knuckle-opener; Fig. 4 is a detail vertical sectional view on the line 4—4, Fig. 65 1, showing the relation of the knuckle opener to the tail of the knuckle and to the lock when the coupler is locked; Fig. 5 is a view similar to Fig. 4, but showing the relation of the knuckle-opener to the lock and to the 70 tail of the knuckle when the coupler is unlocked and the knuckle is thrown open; and Fig. 6 is a longitudinal vertical section of a portion of a car platform and a view in side elevation of a coupler embodying my in- 75 vention.

Like symbols refer to like parts wherever they occur.

As the limitation of space for vertical movement of the locking member of a coupler occurs frequently in passenger equipment, the invention has been shown (see Fig. 80 6) as applied in connection with a passenger car, and also as embodied in that form of passenger couplers wherein the head is 85 pivoted on the stem; but it is to be understood that this has been done without intent to limit the invention to such use.

I will now proceed to describe my invention more fully, so that others skilled in the 90 art to which it appertains may apply the same.

In the drawings, 1 indicates a coupler head which is preferably provided with a pivot opening 1^a whereby it may be pivotally 95 connected with a coupler stem.

Extending transversely of the coupler head in the upper portion thereof is a compartment 2 within which a knuckle opener 4 may be pivoted. The guard arm side of 100 this compartment opens laterally through the coupler head, as at 2^a, to permit the entrance into the head of a lever 7 by means of which the vertically movable locking member 5 may be actuated.

3 indicates a knuckle which is pivoted on the coupler head 1 by a knuckle pin 3^a. The tail 3^b of the knuckle extends into the path

of movement of the knuckle opener 4 and the knuckle opener engages therewith in the act of opening the knuckle.

4 indicates a knuckle opener having the general form of a bell crank lever. It is preferably pivoted on the head at its angle by a pivot pin 4^a. Its long arm 4^b projects downwardly behind the tail 3^b of knuckle 3, and its short arm 4^c extends toward the vertically movable gravity lock 5 so as to be engaged and actuated thereby.

The long or dependent arm 4^b of the knuckle opener 4 is preferably curved or bent somewhat, as indicated in Figs. 4 and 5 of the drawings, and the extremity of the short arm 4^c is preferably inclined or beveled transversely, as at 4^d. As will be understood upon reference to Figs. 4 and 5, the result of the beveling of the face 4^d of the short arm of the knuckle-opener is that the lug 5^a of the lock upon coming into engagement with the beveled face causes the knuckle-opener to tilt, thus causing the lower end of the arm 4^b which engages the tail of the knuckle to perform a curved movement approximating the curvilinear travel of the knuckle in opening, the wear due to the grinding of the knuckle-opener against the knuckle being thereby decreased and the knuckle opener being also thereby enabled to more effectively operate upon the knuckle during the rotation of the latter toward open position.

5 indicates the vertically movable lock or locking member which, if desired, may have the usual guide portion 5^a extending downwardly through a slot or opening in the bottom wall of the coupler head.

The lock 5 is perforated vertically by a curved passage or channel 5^b which opens through the top of the locking block and through the side wall thereof. Within said channel 5^b is a curved link 6 which is movable with respect to the lock 5 and which connects the latter with the lever 7 by which it is operated.

Adjacent to the lower opening of the channel 5^b of the lock and in the side walls of said channel are curved elongated recesses 5^c, as indicated by dotted lines in Figs. 2 and 3 of the drawings. These recesses are for the reception of laterally projecting pivot pins or trunnions which are preferably formed on the sides of the curved link member 6.

At or adjacent to the top of the lock 5 and on the side thereof next to the knuckle opener 4, the lock is preferably provided with a lug or projection 5^a which is formed with a horizontal upper face that is adapted to engage the inclined face 4^d at the extremity of the short arm 4^c of knuckle opener 4 to thereby impart a twisting side motion or rotation to the knuckle opener, the double taper or double coniform shape of the pivot

opening of the knuckle opener as shown in dotted lines in Figs. 1 and 4, permitting such side or twisting motion of the knuckle opener when the latter is actuated by a vertical movement of the lock 5.

5^a indicates a recess on the under inner side of the locking block 5 to facilitate the clearance of the tail 3^b of the knuckle 3.

6 indicates a curved link member which is pivotally connected at one end by a pin 6^a with one arm of an actuating lever 7 and which is connected at the other end with the lock 5 by means of pivot pins or trunnions 6^b. Owing to the width and shape of the passage 5^b in the locking block this link 6 is capable of a vibratory movement to accommodate itself to the various positions assumed by the actuating lever 7, and because of the elongated curved bearing recesses 5^c in the side walls of the channel 5^b the lower end of the link 6, when the locking member 5 is in locked position, can also project through the side wall of the locking member 5 and into the opening 1^b in the inner wall of the coupler-head, thus standing beneath a portion of the coupler head and constituting what is known to those skilled in this art as a lock to the lock.

7 indicates the actuating lever for the lock. It is pivoted to the coupler-head by means of a pivot pin 7^a; and the portion thereof which is adapted to project through the opening 2^b into the coupler head is pivotally connected by a pin 6^a with the link 6 by means of which the lock 5 is raised.

As shown more particularly in Figs. 2 and 3, the lever 7 is preferably provided with a hook 7^b forming means for connecting it with the uncoupling bar or rod R or other means for actuating the lever 7 by the usual or any preferred form of release rigging.

The devices being constructed and combined substantially as hereinbefore pointed out it will be seen that the lever 7 being actuated by the rod R of the release rigging 105 in the usual manner will, through its arm which projects into the coupler head and through its connection within the coupler head with the vertically movable lock 5, effect such a vertical movement of the lock as 115 is requisite to unlock the coupler and actuate the knuckle opener with but a slight encroachment of any of the parts upon the space intervening between the top of the coupler-head and the underside of the car 120 platform.

As the lock 5 rises to the extent of its vertical movement the lug or projection 5^a thereon engages the inclined or beveled extremity 4^d on short arm 4^c of the knuckle 125 opener 4, and, if the vertical movement of the lock member is continued and the knuckle 3 is free to rotate, the continued vertical movement of the lock 5 will impart to the lower end of long arm 4^b of the knuckle 130

opener a rotary movement in substantial conformity to the travel of the tail of the pivoted knuckle 3.

Having thus described my invention, what I claim and desire to secure by Letters Patent is:

1. In a car coupler, the combination of a coupler head having a lateral aperture opening toward the guard-arm side of the 10 coupler head to permit the entrance of a lock actuating lever which is pivoted on the coupler-head and which extends through said aperture to a point above the lock for said knuckle, a pivoted knuckle, a vertically 15 movable lock for the knuckle, a rotatable knuckle-opener lever having its pivotal point above said lock when the latter is in locked position, an actuating lever for the lock, said lever being pivoted on the guard- 20 arm side of the coupler head and projecting laterally into said coupler head when the lock is in locked position and its pivotal point being below the pivotal point of the knuckle-opener lever.
2. In a car coupler, the combination of a coupler-head having a lateral opening for the entrance of a lock actuating lever, a pivoted knuckle, a pivoted lock actuating lever mounted on the guard-arm side of the 30 coupler-head and adapted to project into said head through the lateral opening thereof, a vertically movable lock, said lock having a lateral projection for actuating a knuckle-opener, a link having pivotal connection with the vertically movable lock and with the actuating lever, and a knuckle- 35 opener lever pivoted on the coupler-head and having one of its arms extending into the path of the projection on the lock, the 40 pivotal point of said knuckle-opener lever being above said lock when the latter is in locked position and the pivotal point of said lock-actuating lever being below the pivotal point of said knuckle-opener lever.
3. In a car coupler, the combination of a 45 coupler-head, a knuckle pivotally mounted

thereon, a lock for said knuckle, and a knuckle-opener lever pivotally mounted on said coupler-head, said lock being adapted to actuate said knuckle-opener and said 50 knuckle-opener having a pivot pin aperture which flares in opposite directions.

4. In a car coupler, the combination of a coupler-head, a knuckle pivotally mounted thereon, a lock for said knuckle, and a 55 knuckle-opener lever pivotally mounted on said coupler-head, said knuckle-opener lever having a face which is beveled in a direction transversely of the general swinging movement executed by said knuckle-opener lever 60 and said beveled face being adapted to be engaged by said lock to effect simultaneous swinging movements of said knuckle-opener lever both around the pivot pin of the knuckle-opener as an axis and in the direction of length of said pivot pin.

5. In a car coupler, the combination of a coupler-head, a knuckle pivotally mounted thereon, a vertically movable lock for said knuckle, a pivoted knuckle-opener member 70 75 the pivotal point whereof is above said lock when the latter is in locked position, said knuckle-opener member being adapted to be engaged and actuated by said lock, a pivotally supported lever connected to said lock for actuating the latter, a link movable in the plane of rotation of said lever and pivotally connected to said lever and said lock, and means connected to said lever for actuating the same, the point of connection of 80 the lock actuating lever to its actuating means being adapted to trace a path which intersects the vertical passing through the point of pivotal support of the lock actuating lever.

In testimony whereof I affix my signature, in the presence of two subscribing witnesses.

WILLIAM KELSO.
